RUFUS E. BALL, OF WEBB CITY, MISSOURI.

MINERAL-FAUCET.

1,135,345.

Specification of Letters Patent. Patented Apr. 13, 1915.

Application filed August 27, 1914. Serial No. 858,881.

To all whom it may concern:

Be it known that I, RUFUS E. BALL, a citizen of the United States, residing in Webb City, county of Jasper, and State of Missouri, have invented a new and useful Improvement in Mineral-Faucets, of which the following is a description.

My invention relates to faucets or gates and more particularly to mineral faucets which are adapted for the discharge of mineral matter in a semi-fluid condition or mixed with acids.

Heretofore faucets of this nature have been provided with a wear-piece suitably attached to the lip of the faucet and extending up into the body thereof in such manner as to produce a continuous, smooth surface to the outlet, but experiment has demonstrated that the acids or fluids will work themselves into the interstices between the wear-piece and the body of the faucet in such manner as to corrode the fastening means of the wear-piece and cause the same to drop out. Hence, my present invention has several important objects in view among which are: to provide a means for securing a wear-piece to the body of the faucet, including an impermeable material of a relatively low melting point, so as to form an armored lip at the discharge end of the faucet; to so insert a wear-piece in the gate that the gate is provided with an armored lip; to provide means whereby the gate may be easily detached from the body, and for locking the gate in its closed position for holding the gate at all times tightly against its seat and compensate for wear between the parts; to provide an armored lip for the faucet embracing almost the entire tubular outlet of the faucet and extending up a considerable distance into the body thereof for the purpose of better resisting the erosive action of the moving particles of the mineral matter; to provide means for securing the armored lip to the faucet so that it will resist the action of the alkali water or acids contained in the liquid with which the mineral is mixed; and to provide an armored lip on the inner side of the gate adapted to slide down at an angle over the mouth of the faucet for the purpose of bringing the two armored edges, of the faucet and of the gate, together so as to cut off the flow of material, these edges being adapted to coöperate with each other only during the operation of shutting off the flow

of the material and are then designed to be out of contact.

With the above objects in view and others which will be detailed during the course of this description, my invention consists in the parts, features, elements and combinations of elements all as hereinafter described and claimed.

In the drawings: Figure 1 is a side view of my improved faucet; Fig. 2 is a longitudinal vertical section of Fig. 1; Fig. 3 is a perspective view of the faucet-body and its wear-piece or bushing, the gate and yoke therefor being removed and the wear-piece or bushing of the faucet-lip being detached; Fig. 4 is a fragmentary cross-section on line $\alpha-\alpha$ of Fig. 1; and Fig. 5 is a perspective view of the gate removed from its yoke, showing the interior face, the bushing or wear-piece of the gate being detached.

Referring to the drawings, 2 designates the body of the faucet made of any suitable material, such as cast-iron, and bell-shape in general form. The upper, or inlet, end of the faucet is provided with screw-threads 3, whereby it is adapted to be screwed into or attached to the outlet opening of the jigtank, the polygonal shoulder 4, adjacent to the screw-threaded portions, being provided for the application of a wrench whereby the faucet may be applied or removed. The body is downwardly and outwardly curved from the said inlet end and is formed with a correspondingly-shaped axial passage 5. In order to withstand the wear and tear to which the faucet is more particularly liable at its outlet, I gradually increase the thickness of the body walls in all directions toward the outlet end. The outlet end of the faucet is provided with a convex or arcuate face 2', that is, rounded in the arc of a circle of which the axis of movement of the gate is the center, as later described. The sides of the lower end of the faucet body are exactly parallel with each other, as shown clearly in Fig. 3, and are provided on one side with the opposed stops 6.

A rounded gate or slide is indicated at 7, having the same curvature as the face 2' of the faucet and fitting to slide over said face and to cover or uncover the passage 5 of the faucet. The slide or gate is provided with the inwardly extending flanges 7', shown clearly in Figs. 4 and 5, which, when the gate is in position, extend inward on either side of the face of the faucet-body,

thus holding the gate from any lateral movement. In order to hold the gate in place upon the end of the faucet, I provide a yoke comprising a cross-piece 8 and two inwardly-extending arms 9. At their termination, these arms are provided with U-shaped sockets 9', opening toward the cross-piece of the yoke, these sockets being adapted to engage with studs 10, projecting from the faucet-body and preferably cast therewith. The slide or gate 7, it will be noted, is made separate from the yoke for the purpose of permitting the slide to be forced independently against the face of the faucet and thus take up any wear between the two parts. In order to compensate for wear, I make the cross-bar 8 of the yoke hollow and inclose therein a hollow bow-spring 11, the two ends of which contact with the gate slide 7 and the middle of which is engaged by the end of an adjusting screw 12, which passes through the cross-bar. The screw is provided with a milled head whereby it may be easily turned to compress the spring against the slide and to force the slide or gate into contact with the face 2' of the faucet. A handle 13 is formed on the yoke so that the yoke and gate may be easily manipulated. In order that the yoke may have a positive engagement with the slide or gate 7, I provide the opposite edges of the gate with a pair of lugs 14, between which the arms 9 of the yoke fit, as shown in Figs. 1 and 5. Thus the gate may be shifted relatively to the faucet for any suitable adjustment.

In connection with the stop 6, I provide one of the arms with a screw-threaded stud 6', shown most clearly in Fig. 4, which will come in contact with one or the other of the stops 6 and thus limit the movement of the gate. When, however, it is desired to move the gate entirely away from the face of the faucet as in disengaging the gate and yoke from the faucet, it is only necessary to raise the screw-stud 6', so that its end will escape the lug 6 when the arms may be moved past the lugs. The purpose of this will be hereinafter described.

Preferably, I provide the corresponding ends of the faucet face 2' and of the gate 7 with eyes 15, cast or otherwise formed therewith. These are preferably on the upper end of the gate and faucet face 2' and are adapted to register with each other when the gate is closed. The hasp of a padlock 15' may be passed through these two eyes to hold the gate locked in its closed position. I do not wish, however, to be limited to this exact form of lock.

It is to be particularly noted that the under side of the cross-bar 8 of the yoke fits solidly against the outer face of the gate 7 and thus there is no play between the gate and the cross-bar, but the gate is held in absolute contact with the face of the faucet-

body. The importance of this provision will be pointed out later.

Mineral gates or faucets are subjected to great wear through the abrasion of the flowing material which acts to cut out the passage 5 and particularly the under lip in the manner indicated by dotted lines 2^a, in Fig. 2. This not only lessens the life of the faucet, but such abrasion constantly enlarges the mouth of passage 5, particularly at its 75 under surface, and not only the regulation of the flow is rendered difficult, but the faucet cannot be tightly closed. While faucets made entirely of chilled iron or steel would last longer than ordinary faucets, yet they 80 would not only be costly, but practically impossible, and in order to obviate the disadvantage above referred to, I cut out the inside face of the mouth of the passage 5, as at 5', Fig. 3, and insert therein a U-shaped 85 wear-piece or bushing 16, preferably of chilled steel or iron and in some cases of brass, which when worn down may be easily removed and replaced. Thus not only is the life of the faucet prolonged, but when the 90 lower side of the mouth is the least worn down the faucet is not ruined and it is only necessary to replace the old bushing 16 with the new one, making the faucet as good as ever. In my former patent, #829,816, I 95 have shown such a bushing as held in place by a set-screw. This I have found, however, to be open to the serious objection that liquid passing through the faucet enters into the joint between the bushing and the 100 body of the faucet and that if this liquid contained any acid or alkali, as is usually the case, the acid or alkaline water will eat out a channel for itself in the faucet-body and that this joint or channel will hold the 105 acidified water which will greatly act upon the metal, enlarging the seat, loosening the bushing and ruining the faucet. In order to obviate this, I attach the bushing 16 to its seat by means of Babbitt metal 17, or 110 other analogous material. This fills up the space between the bushing and its seat, sealing the same and absolutely preventing the entrance of water or other liquid into the joint, the Babbitt metal, of course, not being 115 attacked by the acids or the alkaline water. For the purpose of more securely locking the bushing to its seat, I drill shallow holes 5^a in the outside and inside faces, respectively, of the bushing and its seat. The Babbitt metal flows into these holes, interlocks therewith, and securely holds the bushing in place. The Babbitt metal should be in sufficient quantity to make a lining between the parts and space the wear-piece 120 from the socket. Another point of wear in gates of this character is the lower edge of the gate-slide 7. If the gate is partly closed, the passage of the semi-liquid mineral soon acts to wear away this edge. Thus the gate 130

cannot be entirely closed even though the gate-slide is pushed downward to its full extent and, even if no mineral passes, the liquid vehicle soon trickles away. To obviate this and prevent a gate, otherwise good, from being discarded simply because its lower edge is worn, I provide a wear-piece, or flat bushing, 18 of hard metal, such as chilled iron or steel, this bushing being attached to the lower edge of the gate where it will receive the wear of the flowing mineral. I have found it best to form a seat 18^a in the lower edge of the gate on its inside face and to set the bushing in place therein, holding it in position by means of screws or pins 19, passing through openings 20, in the seat 18, and into the bushing 17, as shown in Fig. 2. When the bushing has become worn out, so that the gate no longer closes, it may be taken out and thrown away and a new bushing substituted.

Aside from the advantages above referred to, my improved faucet has a number of others. By reason of the U-shaped sockets 25 at the ends of arms 9, the yoke or slide may be easily attached to or detached from the faucet-body, it being only necessary to turn the yoke on its trunnions to a position at right-angles with the axis of the faucet-body and to push inwardly on the yoke, when the trunnions are forced out of the sockets and the yoke may be drawn away from the faucet. This is of particular value, inasmuch as it permits of the easy substitution 35 of a new gate-slide for one which is worn out without the removal of the faucet itself or for the complete detachment of the yoke and gate-slide to permit of the more convenient insertion of the bushing 16.

It is also to be pointed out that the gate-slide 7 is not held in place solely by the pressure of spring 11, but that the cross-bar 8 fits solidly against the back of the slide. This is of considerable importance as, unless the slide has a practically unyielding backing, the pressure of the semi-fluid material, forced intermittently downward by the action of the jig, will intermittently open the slide to a slight degree against the force of the spring. Some of the material will then be forced between the slide and its seat on the face 2' of the faucet, lodging in this space and holding the valve open. With my construction, however, the spring 11 merely takes up the very slight wear between the face 2' and the slide 7, and acts to compel the slide to conform to any slight irregularities in the face 2' of the faucet; but, it is the yoke itself which resists the pulsations of the semi-fluid current and not the spring 11. The adjustment whereby the spring may be tightened is particularly convenient as thereby the slide may be forced so tightly against the face of the faucet that it cannot be removed without slackening the

tension of the spring. Thus, there is no danger that drays or workmen by accidental contact with the sliding-gate will open the same. Again the bow form of spring is advantageous in that it equalizes the pressure over the entire face of the slide and bears particularly on the edges which come in contact with the edges of the faucet-body. A pressure directed solely to the middle of the slide permits the slide to be forced open 75 at its margins by the pressure of the mass behind.

It is often necessary that faucets, particularly mineral faucets, should be locked positively against any intermeddling or against 80 felonious attempts to extract mineral. To that end, I provide the locking staples 15 and padlock 15', above referred to.

While I have referred to my faucet as being made of cast iron or other metal, I wish 85 it to be distinctly understood that I do not want to be limited as to the material. The faucet might be made of wood and the bushings on the gate and the lip of the faucet of metal; or the faucet-body might be made of 90 metal and the bushings of the same material and of the same degree of hardness, in which case the bushing, while not resisting wear any more than the body of the faucet would, could be very easily removed and new bushings inserted.

I have shown what I believe to be the best form of my invention, but I do not wish to be limited thereto, as it might be embodied in other forms without departing from the 100 spirit thereof.

Having thus described my invention, what I claim and desire to secure by Letters Patent is:

1. A faucet of the character described 105 comprising a body having a central passage therethrough and a segmental socket formed around the lower side of the outlet end of the central passage; a segmental wear-piece inserted in the said socket and spaced therefrom and held therein by fused metal which fills the space, said wear-piece forming an armored lip to the faucet; and a gate for controlling the discharge end of said faucet, said gate having on its inside face at its 110 lower edge a socket, and a removable wear-piece filling said socket.

2. A faucet-body having an arcuate armored discharge end, in combination with an arcuate gate working in contact therewith 120 and provided on its side with a plurality of outwardly-projecting lugs, and a yoke pivotally connected with the faucet-body and set between said lugs, the arms of the yoke embracing the gate and holding the latter 125 in firm engagement with the faucet.

3. A faucet of the character described having an arcuate armored discharge end, in combination with an arcuate gate provided with an armored lip working in con- 130

- 3 tact therewith, a pivoted yoke independent of the gate which holds the gate against the arcuate face of the faucet, the cross-bar of the said yoke having its inside face in contact with the outside of the said gate to hold the same positively against the face of the faucet at the discharge end, and a spring attached to the cross-bar bearing against the gate to force it inward against the face of the discharge end of the faucet.
4. A faucet-body provided with an arcuate armored discharge end, an arcuate gate having an armored lip working in sliding contact with the discharge end thereof and having arms embracing the gate and pivotally connected to the body of the faucet; a channeled cross-bar connecting said arms at the outer end of the said gate; a bow-spring mounted on the said channeled cross-bar and bearing against the outer side of the gate, and means for adjusting the tension of said spring.
5. A faucet-body having an arcuate discharge armored end, in combination with an arcuate gate working in contact therewith and provided on its side with a plurality of outwardly-projecting lugs, and a yoke pivotally connected with the faucet-body, the arms of said yoke engaging between the said lugs whereby the gate may be moved by said yoke.
6. A faucet-body having an arcuate armored discharge end, in combination with an arcuate gate provided with an armored lip and working in contact therewith and provided on its side with a plurality of outwardly-projecting lugs and a yoke pivotally connected with the faucet-body and movable longitudinally thereof, the arms of said yoke engaging between the said lugs whereby a relative radial adjustment may be accomplished between the gate and the yoke.
7. A faucet of the character described, having an arcuate armored discharge end, in combination with an arcuate gate provided with an armored lip working in contact therewith, a pivoted yoke independent of the gate which holds the gate against the arcuate face of the faucet, the cross-bar of the said yoke having its inside face in contact with the said gate to hold the same positively against the face at the discharge end, and a spring attached to the cross-bar and bearing against the gate to force it inward against the face of the discharge end.
8. A faucet of the character described comprising a tubular body having an arcuate discharge end, an arcuate gate working in sliding contact therewith, a yoke having arms which engage the gate and are pivotally connected to the body of the faucet, the upper termination of said discharge end and of the gate being provided with eyes, and means adapted to engage with said eyes for locking the gate to the faucet-body.
- In testimony whereof I have hereunto signed my name in the presence of two subscribing witnesses.
- RUFUS E. BALL.
